UNITED STATES PATENT OFFICE

BRUCE BORLAND, OF CHICAGO, ILLINOIS

SEAL

Application filed November 30, 1929. Serial No. 410,781.

This invention relates to car seals or the like and is particularly directed to seals of this character which are self-locking as distinguished from those requiring a seal press for fastening the same.

The objects of this invention are to provide an improved self-locking seal which may be cheaply manufactured and which will be effective in use; to provide a seal having a locking button provided with catches, and a cap or coacting member having means for engaging with said catches to hold the parts in locked position; to provide a seal having locking members which are covered or protected so that the seal cannot be easily tampered with or unfastened without being broken and to provide such other novel features and improvements in construction as will appear from the following description.

20 In the accompanying drawing illustrating this invention:

Figure 1 is a side view of a complete seal shown in locked position;

25 Figure 2 is an enlarged sectional view of the locking or fastening members shown in partially engaged position;

Figure 3 is a sectional view similar to Figure 2 but showing the parts in engaged or fastened position;

30 Figure 4 is a plan view of a portion of the seal and button;

Figure 5 is a plan view of the cap or coacting engaging end;

35 Figure 6 is a sectional view showing a slightly modified form of construction; and

Figure 7 shows a further modified form of construction.

My improved seal as shown in the drawing, 40 comprises a strip 8 which is preferably formed of metal and which has sealing or fastening members to form a closed loop. In the commercial forms for car seals these strips are formed of tin about $\frac{3}{8}$ of an inch wide. A button or projection 9 is provided adjacent to one end of the strip and is preferably formed integrally therewith. In the forming of this button the edges of the strip are drawn in making recesses 10 which project in approximately to the base of the button and a short tab 11 is left projecting

beyond the button. The top 12 of the button is preferably flattened so that the button will project outwardly as short a distance as possible. This hollow projection or button has one or more tongues or catches 13 in the sides thereof, these tongues being formed by cutting or slitting the sides of the button from the top to the bottom and punching or cutting out sections to form holes 14 at the lower ends of the tongues. The lower ends of the tongues are bent outwardly beyond the adjacent surface of the button and will have a certain amount of resiliency.

The strip 8 is provided with a hollow cap or coacting fastening member for engagement with the button 9. In the particular arrangement shown this cap 15 is formed adjacent to the end 16 of the strip. This portion of the strip is then folded closely upon itself to provide a cover or top 17 for the open cap or projection 15. This cover portion has an inwardly projecting annular flange or bead 18 fitting tightly in the adjacent end of the cap 15 as clearly shown in Figure 2. The strip 8 is again folded so that the cap or projection 15 will pass through a hole 19 in the strip and extend out on the opposite side in position for engagement with the button 9.

The cap or fastening member 15 is turned inwardly at its lower edge to provide locking or fastening means for engagement with the lower ends of the tongues or catches 13. This inwardly turned flange or edge 20 preferably extends around the inner circumference of the cap and fits closely against the base or largest diameter of the button 9.

When the seal is to be fastened or locked, the cap 15 is brought into engagement with the button preferably as shown in Figure 2, one side of the cap being placed over the button until the edge or flange 20 engages with the lower end of the outer tongue 13, and then the button is rocked or swung downwardly until the opposite portion of the flange engages with the tongue or catch 13 on the opposite side of the button. When the parts are thus brought into fastening or locking relation as shown in Figure 3 it will be practically impossible to disengage such fastening members without breaking the seal. It will

be seen that there are only short segments or portions of the seal left connected with the button on either side of the tongue 13 so that the strip will be apt to be broken at this point 5 before the fastening members can be pulled apart. Likewise if it is attempted to pull on the tab or extension 11 this part is apt to be broken off as it only has short connecting portions uniting it with the button. The cover 10 17 fully protects the upper portion of the button so that it is impossible to reach in and release the tongues from engaging position. Furthermore after the flange or rim 20 is in fastening position the lower ends of the 15 tongues will extend over the same so that it will be difficult to disengage the tongues by reaching through the open bottom or end of the button.

However, the ends of these tongues are further protected in the device shown in Figure 20 6 by merely making slits to sever the lower ends and leaving oppositely disposed sections 21 of the sides of the button 22 illustrated in this figure. These sections will further prevent the possibility of tampering with the 25 tongues by means of any tool inserted in the button.

In the device shown in Figure 7 this point is further protected so that there could be 30 no possibility of tampering in this manner. In this arrangement the button 23 is formed adjacent to one end of the strip 24 and a fold made to provide a cover or bottom 25 for the button. This cover portion has an 35 inwardly projecting annular flange 26 similar to the flange 18 shown in Figure 2. Another fold is made in the strip and the button is passed through a hold 27 in the strip 24 thereby making three layers of the strip adjacent to the button. When a locking cap 40 such as the cap 15 is brought into engagement with this type of button, the ends of the tongues 28 will be fully protected both from the lower or underside and the top or cap side 45 and the fastening or engaging portions lock the several plies or layers at the respective ends of the strip so that the fastener cannot be disengaged without injuring the strip.

While I have described my seal in connection 50 with those of the car seal type, it will be apparent that various forms may be made for different purposes and therefore I do not wish to be limited to the particular arrangement or construction shown and described 55 except as set forth in the following claim in which I claim:

A strip having an integrally formed hollow button provided with a plurality of resilient tongues with their free ends adjacent 60 to the strip, said strip having a hollow projection adjacent to the end thereof and folded to form a closure for one end of said projection and folded again with the projection extending through a hole in the strip, said projection 65 having an annular inwardly project-

ing flange adapted to fit closely over the button and to engage with the ends of the tongues when the parts are in fastened position.
